DISTILLATION OF ALCOHOLS FROM AQUEOUS MIXTURES OF ALKYL SULFATES AND SULFURIC ACID

Francis M. Archibald, Elizabeth, N. J., assignor,
by mesne assignments, to Standard Oil Development Company, a corporation of Delaware

Application November 16, 1944, Serial No. 563,745

6 Claims. (Cl. 202—57)

1

This invention relates to the production of alcohols from olefins occurring in cracked petroleum material, and it relates more particularly to a method for more effectively distilling the alcohol from an acid extract.

In the manufacture of alcohols from various olefinic materials, the olefins are absorbed in sulfuric acid to form alkyl esters which remain in the acid as an acid extract. The extract is then diluted with water to hydrolyze the esters to the corresponding alcohols which are recovered by heating in a packed or plate column usually countercurrent to a stream of steam. During the distillation step, the heat of the steam tends to form polymers and free carbon which accumulate in the packing or on the plates of the column and cause foaming, stoppages, and inefficient operation. Cleaning of the stills after shut down is tedious and is a time consuming operation and in some cases requires the use of expensive solvents to break up the tarry and resinous mass formed. Furthermore, much of the polymeric material remains in the diluted acid and upon reconcentration of the acid to its former strength, the polymers are carbonized and precipitate upon subsequent dilution when re-used in the process.

It is therefore one object of this invention to prevent the deposit of such polymeric, tarry and carbonaceous material in the still during the distillation of the alcohol from the extract.

It is a still further object of this invention to provide a process for the production of alcohols from acid extracts in a continuous manner without any periodic shutdown to clean out the still.

Other objects and a further understanding of this invention may be had by referring to the following description and claims taken in conjunction with the accompanying drawing which is a diagrammatical view of the general flow plan of the process.

According to the present invention, the above objects are accomplished by adding a small amount of a non-volatile hydrocarbon oil to the distillation column, used to remove the alcohols from the extracts, at a point below the middle of the column. This results in the dissolving and dispersing of the polymer, and tars, in the oil. This oil is withdrawn from the still with the spent acid and can be easily separated therefrom and disposed of as fuel. The acid resulting from this process is cleaner than when no oil is used and can be reconcentrated and used again for producing acid extracts thereby giving an improved feed product to the distillation column.

Referring more particularly to the drawing, a

2

hydrocarbon feed stock consisting primarily of a C₄ hydrocarbon fraction containing 15-30% butenes is introduced into the bottom of agitator 1, through line 2. Sulfuric acid of about 80-90% strength is introduced by line 3 into the top of agitator 1. The agitator is preferably maintained at a temperature between 25 and 50° C. by means of refrigeration coil 4 and the contents are thoroughly mixed by means of agitator blade 5, so as to form an acid extract containing mono-butyl and dibutyl sulfates which is removed from the bottom of agitator 1 through line 6, and introduced into settler 7 where unreacted butenes and other hydrocarbons are removed through line 8. Acid extract is removed from settler 8 through line 9 and diluted with water introduced through line 10 and passed through orifice 11 into hydrolyzer 12. The mixture of acid extract and water is passed through hydrolyzer 12 at a sufficiently slow rate so that the dialkyl esters and most of the mono alkyl esters are substantially completely converted into alcohol. The hydrolyzed extract is removed from the hydrolyzer through line 13, diluted with water from line 14 to an acid concentration of 45% and introduced into stripper 16 through line 15 at a temperature of about 75° C. In stripper 16 butyl alcohol is stripped from the hydrolyzate by means of a countercurrent stream of steam introduced through line 17 and passed through line 20 to crude alcohol storage for finishing.

During this stripping operation, a portion of the olefins obtained from the acid extract are polymerized to solid materials and partially decomposed to carbonaceous tars which tend to plug up the packing of the column. According to this invention, the deposition of this polymeric and carbonaceous material in the stripping column is prevented by adding a non-volatile petroleum oil to the stripper. This oil is preferably introduced near the middle of the column through line 19. The addition of oil at this point results in dispersing the tar, polymer and carbon in the oil and keeping the plates or packing 40 of the column clean. Acid extract, of approximately 45% concentration containing the oil added through line 19 is removed from the bottom of stripper 16 and introduced into settler 22 by line 21. The acid is allowed to stand until 45 a layer of oil containing polymeric material and carbonaceous material separates out. This oil layer is removed through line 23. Clean spent acid is removed from the settler through line 25 and passed to reconcentrator 24 where it is heated 50 by indirect heat exchange with a high boiling

material such as diphenyl or a mixture of diphenyl and diphenyl oxide. Reconcentrated acid is removed from the reconcentrator 24 by means of line 3 and recycled to agitator 1 for use as the absorption medium therein.

From the above description it is clear that a process has been found whereby the detrimental effects due to the polymerization and decomposition occurring in olefin extracts during distillation of the alcohol therefrom has been overcome by the introduction of a non-volatile hydrocarbon oil into the distillation column in which the alcohol is stripped from the extract. While any non-volatile oil can be used for this purpose, it is preferable to use an oil having a Saybolt Universal viscosity of 100 at 100° F. prepared from a naphthenic base crude. For example, a suitable oil is that obtained by distilling the spent C₄ cut from agitator 1. A suitable oil may also be obtained from the spent acid removed from stripper 16. A certain amount of oil is always produced and can be skimmed from the spent acid and separated from tar by filtering or distillation. The oil may be added in amounts of about 2% of the material feed to the column for a period of one half hour every twenty-four hours. However, it is preferable to continuously feed .05% of oil based on the feed to the column. For example, during the preparation of butyl alcohol as described above, it was found that the addition of about 2% of oil to the stripping column effectively prevented clogging of the plates and difficulties due to such shutdowns were completely avoided.

While the above process has been described in connection with the production of butyl alcohol, this is by way of illustration only, and it is not intended to be limiting since the process is applicable to the preparation of other alcohols such as ethyl alcohol, isopropyl alcohol and higher alcohols, such as amyl alcohol.

The nature and objects of the present invention, having thus been set forth and the specific examples of the same given what is claimed as new and useful and desired to be secured by Letters Patents is:

1. In a process for recovering alcohol from an aqueous mixture of alkyl sulfates and sulfuric acid, in which the acid has a concentration of about 45%, by distillation of the mixture to remove alcohol therefrom and wherein polymers, tars, and free carbon are formed as a result of the distillation, the improvement which comprises carrying out such distillation in the presence of a small amount of a hydrocarbon oil

which is non-volatile under the distillation conditions and which is a flux for the polymers, carbon, tars, etc.

2. The improvement according to claim 1, in which the non-volatile hydrocarbon oil is added to the aqueous mixture during the distillation step in the amount of about 2% of the aqueous mixture fed to such step for a period of one half hour every twenty-four hours.

3. The improvement according to claim 1, in which the non-volatile hydrocarbon oil is added to the aqueous mixture continuously during the distillation step, in the amount of about 0.05% of the mixture fed to such step.

4. The improvement according to claim 1, in which the non-volatile hydrocarbon oil is a naphthenic base oil having a Saybolt Universal viscosity of about 100 at 100° F.

5. In a process for recovering alcohol from an aqueous mixture of alkyl sulfates and sulfuric acid, in which mixture the acid has a concentration of about 45%, by distillation of the mixture in a distillation zone from which alcohol is removed overhead and spent acid from the bottom of the zone and wherein polymers, tars, and free carbon are formed as a result of the distillation, the improvement which comprises adding to the aqueous mixture fed into said distillation zone a hydrocarbon oil which is non-volatile under the distillation conditions and which is a flux for the polymers, carbon, and tars, whereby these distillation decomposition products are dispersed and dissolved in the oil, withdrawing the oil from the bottom of the distillation zone with the spent acid, separating the non-volatile oil and decomposition products from the spent acid, and reconcentrating said acid.

6. The improvement according to claim 5, in which said non-volatile hydrocarbon oil is added to the aqueous mixture during the distillation step, and at a point below the middle of the distillation zone.
